DESIGN FOR A FISHING REEL

Louis Gurrieri and Salvatore Gurrieri,
New York, N. Y.

Application March 24, 1937, Serial No. 68,390

Term of patent 3½ years

To all whom it may concern:

Be it known that we, Louis Gurrieri and Salvatore Gurrieri, subjects of the Kingdom of Italy and residents of the city and State of New York, have jointly invented a new, original, and ornamental Design for Fishing Reels, of which the following is a specification, reference being had to the accompanying drawing, forming a part thereof.

We claim:

The ornamental design for a fishing reel substantially as shown.

LOUIS GURRIERI.
